UNITED STATES PATENT OFFICE.

MARCEL GODEFROY, OF NEW YORK, N. Y.

FABRICATED BEADWORK.

Application filed December 7, 1922. Serial No. 605,532.

To all whom it may concern:

Be it known that I, MARCEL GODEFROY, a subject of the Republic of France, residing at New York city, in the county of New York and State of New York, have invented new and useful Improvements in Fabricated Beadwork, of which the following is a specification.

This invention relates to a fabric-like material which may be made of genuine or imitation pearls or other precious or semi-precious stones, glass, or metal beads, which is especially adapted for use in producing ornate designs in bracelets, necklaces, handbags, hair ornaments, dress trimmings, and similar articles.

Bead-work is usually made up by taking beads, stringing them and crocheting the finished article from the string of beads. Other types of beaded articles are made by stringing beads on a number of parallel strings which are held in a frame, and then weaving other beads and threads into place. Neither of these methods is well suited for factory production, and articles made in this manner have the disadvantage in that should a thread break a great many beads will be lost before the break can be repaired; and it is difficult, if not impossible, to properly repair the same.

According to the present invention there has been devised a type of bead-work (the term bead-work being used in its broadest sense for the purposes of the present disclosure) which is capable of ready production and which, when completed, presents a most pleasing and beautiful appearance. The structure is also extremely strong so that there is little likelihood of breakage with the resultant loss of the beads or the like, each bead being held in place by a multiplicity of elements so that the strain imposed upon any single element is exceedingly small. To enhance the security of the work I prefer to use strong fine wire, as it has excellent wearing qualities and also lends itself readily to the practice of my invention.

In the accompanying drawings there is shown for purpose of illustration one of the embodiments in which my invention may take form, it being understood that this showing is for the purposes of illustration

only, and that the invention is not limited to the precise details shown in the drawing. 55

Figure 1 of the drawing illustrates a section of bead-work made in accordance with the present invention, part being in section and part being in elevation; and

Fig. 2 is a sectional view taken through 60 a bead at right angles to the plane of Fig. 1.

The article may be considered to be supported from a small wire 3, which is strong enough for fastening the bead-work to a frame or clasp or the like. The wire 3 65 passes through a plurality of wire loops 4. These wire loops may be made in any fashion, as for example by collapsing a wire ring. The loops 4 are arranged in pairs, and the middle portion 5 of each is squeezed 70 together as indicated in Fig. 2. The middle portion 5 of the loops 4 of each pair is passed through a bead 6, the lower portion 7 of the loops 4 of each pair is opened, as indicated in Fig. 2, and is deflected outwardly as indicated in Fig. 1. The arrangement for fastening on these end beads is such as to provide a foundation for further weaving of the beads. The bead-work or fabrication of the material may be continued in the following fashion: A loop 8 of wire is threaded through the open lower 75 ends 7 of one of the loops 4, then through a bead 9, then through the lower end 7 of the adjacent loop of the corresponding 80 pair, then downwardly, as indicated in the drawing, through a bead 10, the end of the loop 8 extending below the bead 10 in such a fashion as to present an open eyelet similar to the lower end 7 of the loops 4. The 85 other end of the loop 8 passes downwardly through a bead 12, similarly located to the bead 10, and the lower extremity 13 is disposed in a manner similar to the other end 11. 95

The drawing indicates two of the loops 8 together with the beads attached to these loops. The corresponding elements are numbered with the same reference characters with a prime attached. It is obvious 100 that any number of beads 6 can be used to start the first horizontal row of beads, and that the string of beads can be made of any length desired; all that is necessary is to provide a sufficient number of beads 105 and loops 8. Further, it will be noted that

the general configuration of the bent loops 8 is U-shaped and that the ends adjacent to the loop are so interlaced as to make a rectangular frame having four beads one on 5 each of the sides of the frame.

It will be noted that of the bead-work there will be provided twice the number of wires that it has in the other direction. This 10 is an important feature, as it provides for maximum strength in the direction in which the greatest strains are usually taken.

As wires are used, there is very little danger of breakage such as in articles in which 15 thread is used as at present. The beads themselves are exceedingly strong, and it is very seldom that one will be broken. Any breakage that could occur, whether it will be the breaking of a bead or the breaking 20 of one of the wire loops, will not result in unraveling and consequent destruction of the entire piece of bead-work. This arrangement of making bead-work I have found to be especially well adapted for any structure 25 in which the maximum of flexibility and strength is desired. A fabric woven in this manner is exceedingly flexible; in fact, a length having four beads in a row can be doubled upon itself, the fabric being soft 30 in that it presents but little resistance to flexing in any direction.

This method of arranging and tying the beads is also especially valuable in that artistic designs without limit can be readily

worked out by selecting beads of different 35 colors.

I claim—

1. A fabricated material composed of beads carried on a flexible frame consisting of lengths of wire shaped to form open 40 end loops, the extremities of each of said loops being interlocked with adjacent loops, certain of the beads holding the adjacent loops together to continue the fabric laterally.

2. A fabricated material comprising a frame formed of loops having open ends small enough to be passed through the central orifices of beads, the free ends of the adjacent loops being interconnected to maintain the components of the frame in assembled relation, certain of the beads holding adjacent loops together to continue the fabric laterally.

3. A fabricated material having a flexible 55 frame comprising strands of wire shaped to form loops having three sides, the free ends of said loops being small enough to be passed through beads, and means for interconnecting the extremities of adjacent 60 loops whereby the beads will be supported in a series of rows, the beads in certain series being carried on the abutting portions of the contiguous loops.

MARCEL GODEFROY.
